ATTORNEYS

UNITED STATES PATENT OFFICE.

ABRAHAM WILLIAM WOLFSON, OF NEWARK, NEW JERSEY.

UMBRELLA.

Application filed August 22, 1924. Serial No. 733,635.

To all whom it may concern:

Be it known that I, ABRAHAM WILLIAM WOLFSON, a citizen of the United States, and a resident of Newark, in the county of 5 Essex and State of New Jersey, have invented a new and Improved Umbrella, of which the following is a full, clear, and exact description.

This invention relates to umbrellas, and 10 more particularly to umbrellas, parasols and similar devices, and I would have it understood that hereinafter while I shall refer to the device as an umbrella I use this term in its broadest sense to cover any 15 analogous device.

An object of the invention is to improve upon the construction disclosed in Patent No. 892,473, granted July 7, 1908, to H. G. Walters, and the invention is directed particularly to an improved construction of 20 rib fulcrum and collar with improved coupling means whereby the rib coupling is prevented from turning movement when the umbrella is open, and the rib fulcrums 25 are capable of movement away from the collar when undue wind pressure is had with a tendency to turn the umbrella wrong side out. The parts of this invention are, therefore, substantially the same as those 30 of the patent above referred to except that a difference in the construction of the rib fulcrum and collar constitutes the invention per se.

With these and other objects in view, the 35 invention consists in certain novel features of construction and combinations and arrangements of parts which will be more fully hereinafter described and pointed out in the claims.

40 In the accompanying drawings—

Figure 1 is a view in section, partly in elevation, showing the umbrella in open position and provided with my improvements;

45 Figure 2 is an enlarged view showing my improved rib fulcrum and collar in longitudinal section on the rod;

Figure 3 is a view in transverse section on the line 3—3 of Figure 2;

50 Figure 4 is a perspective view of my improved rib fulcrum.

1 represents the umbrella rod to which a collar 2 is secured by a pair of rivets 3 projecting at right angles to each other and 55 through the rod and collar, the lower por-

tion of the collar being flared or enlarged so as to receive my improved rib fulcrum 4. This rib fulcrum 4 is made with recesses 5 adapted to receive the rivets 3, and it will be noted that the outer ends of the recesses have their walls slightly rounded so as to guide them into operative engagement with the rivets or pins, and that the depth of two opposed recesses is less than the depth of the other pair of recesses so that 60 when the fulcrum is in position in the collar the rivets or pins are located in the ends or base portions of the recesses.

By reason of this construction the rib fulcrum is properly guided into interlocking engagement with the rivets or pins of the collar and a strong and durable engagement is had. This part of the umbrella is necessarily subjected to considerable wear as the umbrella is frequently opened and 75 closed and there is some movement always when the wind is high so that it is desirable that this engagement be such as to prevent undue wear. Therefore, by providing four recesses with a pair of pins or rivets a plurality of contact points is had which insures a proper coupling and prevents undue wear, which would be the case with a reduced 80 number of recesses and contact points with the pins or rivets.

85 While the invention is not limited, of course, to the particular arrangement of parts, I preferably employ the arrangement set forth in the patent above referred to in which the ribs 6 are connected to the fulcrums 4 and the stays 7 connect the ribs with the runner 8 on rod 1. The umbrella cover 9 is connected at its outer end to the ribs 6 and at its inner end is secured under a cap 10 in any approved manner.

95 By reason of the construction above described, the fulcrums 4 can move away from the collar 2, as indicated by dot and dash lines in Figure 1, and will spring back into engagement in the recesses 5 when permitted. 100 The invention therefore is a distinct improvement over the Walters patent above described and the claims hereinafter set forth are directed to such improvement.

Various slight changes and alterations 105 might be made in the general form of the parts described without departing from my invention, and hence I do not limit myself to the precise details set forth but consider myself at liberty to make such slight changes 110

and alterations as fairly fall within the spirit and scope of the appended claims.

I claim:

1. In an umbrella, the combination with a rod, a collar on the rod, a cover secured over the collar, a rib fulcrum mounted to move on the rod, ribs connected to the fulcrum and to the cover, a runner on the rod, stays connecting the ribs and the runner, said fulcrums adapted to move into the collar, a pair of rivets or pins projected through the collar and through the rod, and said fulcrum having recesses therein receiving the pins or rivets.
- 15 2. In an umbrella, the combination with a rod, a collar on the rod, a cover secured over the collar, a rib fulcrum mounted to move on the rod, ribs connected to the fulcrum and to the cover, a runner on the rod, stays connecting the ribs and the runner, said fulcrum adapted to move into the collar, and a pair of rivets or pins projected through
- 20

the collar and through the rod and said fulcrum having recesses therein receiving the pins or rivets, said recesses in the collar being of a length to seat the rivets or pins in the bottoms or bases of said recesses when the rib coupling and collar are together.

25 3. In an umbrella, the combination with a rod, a collar on the rod, a cover secured over the collar, a rib fulcrum mounted to move on the rod, ribs connected to the fulcrum and to the cover, a runner on the rod, stays connecting the ribs and the runner, said fulcrum adapted to move into the collar, a pair of rivets or pins projected through the collar and through the rod and said fulcrum having recesses therein receiving the pins or rivets, said recesses in the collar being of a length to seat the rivets or pins in the bottoms or bases of said recesses when the rib coupling and collar are together.
